UNITED STATES PATENT OFFICE.

JOHN W. BARRON, OF BOSTON, MASSACHUSETTS, ASSIGNOR TO EDWARD F. HAGAR, OF SAME PLACE, AND HENRY SAWYER, OF CHELSEA, MASS.

ZINCOGRAPHY.

SPECIFICATION forming part of Letters Patent No. 310,638, dated January 13, 1885.

Application filed January 7, 1884. (No model.)

To all whom it may concern:

Be it known that I, JOHN W. BARRON, of Boston, in the county of Suffolk and State of Massachusetts, have invented certain Improvements in Zincography, of which the following is a specification.

This invention relates to the process of zincography, or printing from etched zinc plates. It is well known to those skilled in this art that the ink is liable to adhere to the larger depressed or open surfaces between and around the printing lines or surfaces on the plate, the moisture applied by the damping-roller before the application of the ink being incapable of protecting said surfaces from the printing-ink unless mixed with an astringent such as nut-gall, which is objectionable, because it attacks the material in which the design is formed on the plate and renders the plate incapable of producing as many impressions as it would do if no astringent were used. These difficulties have heretofore made zincography impracticable for the production of pictures or designs having any considerable open spaces between and around the lines composing the picture or design, and the process has therefore been confined chiefly to the production of such pictures or designs as have no extended open or unprinted surfaces within the limits of the zinc plate.

My invention has for its chief object to provide means whereby the larger open surfaces between and around the printing lines or surfaces may be protected, so that the printing-ink will not adhere to them; and to this end it consists in perforating said open surfaces to form small orifices extending through the plate, and supplying said orifices with an absorbent which will receive water from the damping-rolls and allow said water to ooze out under the pressure of the inking-roller, thus insuring a sufficient film of water between the inking-roller and the surfaces surrounding said perforations to prevent the ink from adhering to said surfaces, the perforations being minute reservoirs from which the water is expressed by the pressure of the inking-roller, so that the water deposited by the damping-rollers, instead of being displaced or forced off from the non-printing or open surfaces by the pressure of the inking-roller, is held in reserve

to be expressed and caused to flow over the non-printing surfaces when the inking-roller passes over said surfaces.

My invention also consists in applying a backing of copper to the zinc plates for the purpose of strengthening the plate and protecting it against the chemical action of certain absorbents of water which may be employed, as hereinafter described.

Of the accompanying drawings, forming a part of this specification, Figure 1 represents a face view of an etched zinc plate embodying my invention. Fig. 2 represents an enlarged section on line *xx*, Fig. 1. Figs. 3 and 4 represent views of a modification.

The same letters of reference indicate the same parts in all the figures.

In carrying out my invention I prepare a zinc plate for printing by applying a design thereto, etching to depress or eat away the surface between and around the lines, any of the well-known and usual methods of applying the design and etching the plate being employed.

In the open surface between and around the lines of the design I form small perforations or reservoirs, which may be made by drilling or punching through the plate to form independent orifices *a* at any desired distances apart, or by forming the zinc plate on a backing of copper wire-cloth, as hereinafter described.

To the back of the perforated plate I apply a suitable absorbent, which enters or communicates with the orifices, and is adapted to hold water and yield the same when pressure is exerted upon the plate, as by the inking-roller, said pressure causing the water to ooze in small quantities from the orifices upon the surrounding surfaces of the plate. I prefer to employ glue as said absorbent, a coating of the glue of any desired thickness being applied to the back of the plate and confined by sheets of papers or any other suitable material applied to the back of the coating. The glue preferably projects into the perforations and partially fills them. A part of the water applied to the plate, as usual, by the damping-rollers, which are passed over the plate before the inking-rollers, enters the orifices, and is wholly or partially absorbed by the glue.

When the inking-rollers pass over the plate, their pressure causes the water to exude from the saturated glue and spread thinly over the surrounding surfaces of the plate, thus effectually protecting said surfaces from the ink, the inking-rollers being unable to sweep the water from the plate by their rolling action in consequence of the reserve-supply oozing from the orifices.

10. This improvement enables zinc plates to be used for work which has hitherto been performed only by lithographic stones, and thus a great saving in cost is effected.

15. The zinc plates may be applied to cylinders in cylinder-presses, which is obviously impossible with lithographic stones.

I prefer to mix chrome alum with the glue to harden it and keep it from being dissolved too freely by the action of the water. I do not limit myself, however, to glue as an absorbent, as other materials may be used which may be proved suitable. Asphaltum may be found desirable, and I contemplate using potter's clay in some cases. A layer of felt or 25 other suitable textile fabric may be used; but more care would be required in using it, because of its liability to absorb and give out water too freely.

I prefer to coat the back of the zinc plate 30 with copper by electro-deposition, for the purpose of strengthening the plate and preventing it from cracking, and also to prevent chemical action of the chrome alum in the glue on the zinc plate. The face of the plate is protected by a suitable coating while the back is being coppered. After the plate is etched the open spaces around the printing lines or surfaces may be thinly coated with copper, either by electro-deposition or mechanical precipitation, to form a surface which will not receive printing-ink so readily as zinc, the smallest practicable quantity of copper being applied, so that the face of the plate will not be appreciably raised.

The reservoirs may be formed by securing 45 a zinc plate to a sheet of copper wire-cloth and etching the plate to remove all the zinc surrounding the printing-surfaces, thus exposing the wire-cloth.

The absorbent is applied to the back of the 50 wire-cloth, and the meshes of the latter constitute reservoirs, which are equivalents of the independent orifices above described. Fig. 3 shows a front view of a portion of a plate thus formed, and Fig. 4 an enlarged section on line 55 *y y*, Fig. 3.

I claim—

1. A zinc plate prepared for printing and provided with perforations or reservoirs in its 60 open spaces, as set forth.

2. A zinc plate prepared for printing and provided with perforations or reservoirs in its open spaces, and with an absorbent of water in or communicating with said reservoirs, as set forth.

3. A zinc plate prepared for printing and provided with perforations or reservoirs in its open spaces, and with a backing of glue, as set forth.

4. A zinc plate prepared for printing and provided with perforations or reservoirs in its open spaces, a backing of glue or its equivalent, substantially as described, and a confining sheet or sheets of paper applied to the back of the glue, as set forth.

5. A zinc plate prepared for printing and provided with a backing of copper, whereby the plate is strengthened and protected against chemical action, as set forth.

In testimony whereof I have signed my name 80 to this specification, in the presence of two subscribing witnesses, this 2d day of January, 1884.

JOHN W. BARRON.
